UNITED STATES PATENT OFFICE

CHARLES M. HEUBLEIN, OF CHICAGO, ILLINOIS

CURTAIN FIXTURE

Application filed April 6, 1929. Serial No. 353,059.

My invention relates to window attachments, and particularly to novel means adapted for use as a support for lace or similar curtains for windows. The device herein described is an improvement on that disclosed in my Patent No. 1,619,256, of March 1, 1927.

An object of my invention is to provide simple means adapted to be attached to the 10 sashes of vertically sliding windows that shall support the decorative curtains in the usual manner, and shall automatically move the curtain vertically to the extent of the movement of the sash when the window is 15 opened. This serves to remove the curtain from the immediate path of an incoming current of air, eliminate swinging and swaying of the curtain and prevent soiling thereof.

Another improvement relates to the means 20 for mounting the curtain at the top and an intermediate point in the height of the window, adapting the rods and brackets to variations in the length of the curtain, either due to shrinkage or to the substitution of curtains with differently spaced connections for the rods.

Another improvement relates to the substitution of shorter curtain rods supported at one end only for the intermediate curtain- 30 carrying attachment, thus eliminating a bare exposed rod at a point midway of the height of the window when the curtains are drawn back. With these rod-carrying brackets is associated a tie-back hook for holding the 35 curtains in draped or retracted position.

Another important improvement is the provision of a temporary bracket adapted to be associated with the intermediate brackets when the windows are to be washed, for re- 40 taining the curtains in a position out of the zone of operations of the window-washer.

The structure utilized for accomplishing the described purposes will be better understood by reference to the accompanying 45 drawings, in which,—

Fig. 1 is a front elevation of a window to which my improvements have been applied;

Fig. 2 is a vertical sectional view through 50 the window;

Fig. 3 is an enlarged plan view of the upper brackets and rods for supporting the curtain;

Fig. 4 is a similar plan view of the intermediate rods and brackets; 55

Fig. 5 is an enlarged side elevation of one of the intermediate brackets;

Figs. 6 and 7 are sectional views on the lines 6—6 and 7—7, respectively, of Fig. 5; 60

Fig. 8 is a side elevation showing the window-washing arm in place; and

Fig. 9 is a sectional view on the line 9—9 of Fig. 8.

In the drawings, I have illustrated a window including a casing 10 and the upper 65 and lower sashes 11, 12 of a double-hung window.

The upper curtain-supporting members comprise a pair of brackets 13 each having an attaching flange 14 by which the bracket is secured to the upper sash near the top thereof. Openings 15 in the bracket provide for the mounting of the shade curtain therein in the usual manner. At its outer end, each bracket is provided with a thumb screw 16 which serves as the holding means for a pivoted arm 17. The pivot end of the arm is provided with a lateral lug 18 that registers with one of the notches 19 formed in the outer end of the bracket 13 when the arm is 70 in operative position. Three of such notches are shown, adapting the arm for adjustment into three positions, the most elevated of which is shown in Fig. 5. The adjustment is secured by backing off the thumb 75 screw until the lug 18 is free from the notches, then adjusting the arm to the desired position and restoring the thumb screw to a tight condition. This provides for adjustment of the curtain support to correspond to a variation in the length of the curtain.

The intermediate brackets, two of which are required, are best shown in Figs. 2, 8 and 9. They comprise an angular body portion having an attaching flange 20 by means of

which the bracket is secured to the upper end of the lower sash 12, and a supporting portion 21 adapted to carry the pivoted arm 22. The arm is secured in the position shown by means of a screw 23, and, if desired, an interme- 95 100

diate washer 24. A lateral projection 25 on the pivot end of the arm is adapted to register with notches or apertures 26 formed in the metal of the attaching portion 21 for adjustment in the same manner as that already described in connection with the upper supporting arm. A hook 27 is secured to the arm 22 in any desired manner and serves as a means of attachment for a curtain tie-back.

10 Formed at the junction of the portions 20, 21 of the intermediate bracket is a socket 28, preferably of non-circular cross section, adapted to receive the similarly shaped lower end 29 of a relatively long arm 30. This arm 15 has a stud 31 projecting laterally from its free end, adapted to receive the intermediate curtain rod 32 to remove and support the curtain from the immediate area around the window to prevent the soiling of the curtain 20 during window-washing operations. This is best shown in dotted lines in Fig. 2. In operation, the window-washer merely inserts the two arms 30 into the sockets, slips the curtain rods 32 from their connecting studs 25 33 on the intermediate brackets, and places the rods on the studs 31 on the arms.

In normal operation of the window, the curtains being supported at their upper ends 30 on the rods 34 and at their intermediate portions on the rods 32, the raising of the lower sash or the lowering of the upper sash will, in either or both cases, remove the curtains from the path of a body of air moving through the openings. A loop 35 on the curtain may engage the hook 27 on the intermediate bracket to retain the curtain in a draped position. In this condition there is no rod extending across the open space at an intermediate point in the height of the window. 40 The connection between the curtain and the short intermediate rods 32 may be by means of small loops or rings sewed to the curtains on the inside. Thus, in case of shrinkage or the substitution of other curtains, the provision for adjustment of the supporting rods 45 is a desirable one.

Obviously, the construction is capable of much modification, and I do not wish to be limited except as indicated in the appended 50 claims.

I claim:

1. The combination with the sash of a window one of which is vertically slideable, of two pairs of brackets one pair being secured to 55 the top of the window and adapted to support a curtain and the other pair being attached to said slideable sash at a point intermediate the height of the window, laterally projecting studs carried by the lower pair of brackets, and independent sections of curtain rods mounted on said studs and connected to said curtain, the total length of said rod sections being less than the space between 60 said brackets.

65 2. The combination with a window having

a sliding sash, of a pair of brackets and a rod for supporting a curtain at its upper end, a second pair of brackets secured to the sliding sash, a separate rod carried by each of 70 said second pair of brackets, said rods being adapted to be secured to a curtain at a point below its top end, the combined length of said two rods being materially less than the space between said brackets.

3. The combination with a window having 75 a sliding sash, of means for supporting a curtain at the top of said window, a pair of brackets secured to said sliding sash, rods carried by the brackets, and means for adjusting the height of the rods relative to the 80 brackets.

4. The combination with a window having a sliding sash, of upper and lower brackets, the upper brackets being secured to the upper 85 part of a window and the lower brackets being secured to a sliding sash, relatively short independent sections of curtain rod carried by said lower brackets, and means permitting vertical adjustment of said curtain rods relative to said lower brackets.

5. The combination with a window having 90 two sliding sashes, of upper and lower pairs of brackets secured to said sashes respectively, curtain rods carried by said upper and lower brackets, said upper rod being adapted 95 to support a curtain at its top end and said lower rod being secured to said curtain at a point below the top end thereof and means on the brackets for effecting adjustment of the spacing between said upper and lower 100 curtain rods.

6. The combination with a double-hung window having vertically sliding sashes, of two pairs of brackets secured to the upper 105 and lower sashes respectively, rods carried by said brackets adapted to be connected to and to support a curtain at two different points in its length, the rods carried by the lower brackets being supported only at one 110 end and being unsupported at their outer ends with a substantial space intervening between the ends of the rods.

7. The combination with a double-hung window having vertically sliding sashes, of two pairs of brackets secured to the upper 115 and lower sashes respectively, rods carried by said brackets adapted to be connected to and to support a curtain at two different points in its length, the rods carried by the lower brackets being supported only at one end and being unsupported at their outer ends with a substantial space intervening between the ends of the rods, and means on said 120 brackets for adjusting the vertical spacing between the upper and lower rods.

8. The combination, in a double-hung window having upper and lower sliding sashes, of a pair of brackets secured to the upper sash near its upper end and a pair of brackets secured to the lower sash near its upper end, 125

means carried by the brackets for supporting curtain rods, the curtain rods supported by the lower brackets consisting of short sections having a total length less than the space between the brackets, and means in the connection between the upper curtain rod and the upper bracket permitting oscillation of the rod to adjust the height of the curtain.

9. The combination, in a double-hung window having upper and lower sliding sashes, of a pair of brackets secured to the upper sash near its upper end and a pair of brackets secured to the lower sash near its upper end, means carried by the brackets for supporting curtain rods, the curtain rods supported by the lower brackets consisting of short sections having a total length less than the space between the brackets, means in the connection between the upper curtain rod and the upper bracket permitting oscillation of the rod to adjust the height of the curtain, and means in the connection between the lower rods and their respective brackets for also adjusting the height of the curtain.

25 10. In a device of the class described, the combination of a pair of brackets adapted to be secured at the upper portion of a window, a rod supported by said brackets and adapted to carry a curtain, a second pair of brackets adapted to be secured to a sliding sash of said window, rods carried by said second pair of brackets, said last named rods being secured to said curtain at a point below the top end thereof, means in said lower brackets providing sockets, and emergency arms adapted to be mounted in said sockets to support the curtain at a point a substantial distance away from said window.

11. In a device of the class described, the combination, in a window having sliding sashes, of means at the upper portion of the window for supporting a curtain, means at a lower point in the window and attached to a sliding sash for supporting the curtain at a lower point, and a temporary bracket adapted to be carried by a lower bracket and to receive and hold the curtain at a point a substantial distance away from the window.

50 12. In combination, means for supporting a curtain at the upper part of a window, a pair of brackets connected to a lower sash, means carried by said brackets for supporting a curtain rod adapted to be connected to the curtain at a point below its upper end, a temporary arm adapted to be mounted in one of said lower brackets and projecting a substantial distance laterally away from the window, and means on said arm adapted to receive the curtain rod carrying the curtain and thereby to support the curtain at a point away from the window.

13. The combination with a window having sliding sash, of means for supporting a curtain at the upper portion of said window,

brackets secured to a sliding sash and located at a point below the upper end of the window, short sections of curtain rod carried by said lower brackets, said short sections of rod being secured to said curtain at a point below the upper end thereof, and hooks carried by said lower brackets to provide a tie-back for said curtain.

14. The combination with a window having upper and lower sliding sashes, of brackets attached to said respective sashes, curtain rods supported by said brackets, said curtain rods being adapted to support a curtain at two different points in the length thereof, means in the connection between the curtain rods and the brackets permitting oscillation thereof to effect adjustment in the height of the curtain, the lower curtain rod being formed in two aligned unconnected sections, and means carried by the lower brackets for effecting a tie-back of the curtain on short rod sections.

15. The combination with a window having a lower sliding sash, a pair of brackets attached to said sliding sash at the top side edges thereof, said brackets being of reversed duplicate construction and comprising a rebent strip of sheet metal, having a portion adapted to contact the sash, the adjacent portion extending outwardly from the sash and carrying thereon means for supporting a section of curtain rod, the rods carried by each of said brackets being of substantially less length than the width of the sash, and means on said brackets for adjusting the angular position of said curtain rods from the horizontal.

16. The combination with a window having a lower sliding sash, a pair of brackets attached to said sliding sash at the top side edges thereof, said brackets being of reversed duplicate construction and comprising a rebent strip of sheet metal, having a portion adapted to contact the sash, the adjacent portion extending outwardly from the sash and carrying thereon means for supporting a section of curtain rod, the rods carried by each of said brackets being of substantially less length than the width of the sash, means on said brackets for adjusting the angular position of said curtain rods from the horizontal, and means carried by said outstanding brackets for providing a tie-back for a curtain.

17. The combination with a window having a lower sliding sash, a pair of brackets attached to said sliding sash at the top side edges thereof, said brackets being of reversed duplicate construction and comprising a rebent strip of sheet metal, having a portion adapted to contact the sash, the adjacent portion extending outwardly from the sash and carrying thereon means for supporting a section of curtain rod, the rods carried by each of said brackets being of substantially less

length than the width of the sash, means on said brackets for adjusting the angular position of said curtain rods from the horizontal, means carried by said outstanding brackets for providing a tie-back for a curtain, and a temporary bracket adapted to be carried by said bracket and to receive and hold a curtain a substantial distance away from a window.

10 In testimony whereof I have affixed my signature.

CHARLES M. HEUBLEIN.
